BY
Oscar F. Lutz ATTORNEY

UNITED STATES PATENT OFFICE.

MYRON A. SMITH, OF ROCKVILLE CENTER, NEW YORK.

CRUSHING-ROLLER.

1,089,017.

Specification of Letters Patent.

Patented Mar. 3, 1914.

Application filed October 21, 1913. Serial No. 796,422.

To all whom it may concern:

Be it known that I, MYRON A. SMITH, a citizen of the United States, and a resident of Rockville Center, in the county of Nassau and State of New York, have invented certain new and useful Improvements in Crushing-Rollers, of which the following is a specification.

This invention relates to improvements 10 in crushing rollers such for example as are used for granulating material, for example, chocolate or for other similar purposes.

Heretofore such rollers have been made of chilled cast iron and bored out so as to form 15 a chamber into which cooling water was admitted and circulated for the purpose of cooling the roller, as the same becomes heated by friction. The cooling water cools the circumferential or cylindrical part of the 20 roller between the ends, but on account of the greater mass of iron at the ends, the ends do not become cooled to the extent of the central part, which sets up an uneven 25 expansion and contraction in the roller and as a result thereof the periphery is no longer 30 true and the roller does not crush or grind properly and must eventually be stopped to permit it to cool as otherwise such irregular 35 expansion constantly brings the roller to a still greater extent out of true until it is practically worthless as a grinder, for the 40 time being.

The object of my invention is to provide 45 a new and improved grinder or crushing roller which is so constructed that the cooling water cannot affect it in such a manner that a variable expansion or contraction 50 does not take place in the different parts of the roller, but on the contrary the cooling effect is uniform throughout the entire roller thereby preventing such irregularity of expansion or contraction which would make 55 the periphery of the roller untrue.

This improved roller does not become unduly heated and grinds and crushes as perfectly at any time of operation as it did at the beginning and which roller is simple in construction, strong, effective and reliable and not expensive.

50 In the accompanying drawings in which like letters of reference indicate like parts in all the figures:—Figure 1 is a perspective view of one embodiment of my improved crushing roller, parts being broken away 55 and others shown in section. Fig. 2 is a longitudinal sectional view through the roller.

Fig. 3 is a transverse sectional view on the line $\alpha-\alpha$ of Fig. 2.

The roller 1 is made of chilled iron and is in the form of a true cylinder with the two closed ends 2. It is cast with a core of variable diameter so that the bore of the cylinder is of variable diameter and therefore the thickness of the peripheral or cylindrical wall is variable. As the greatest quantity of metal in cross section of the roller is found at the ends and the cooling water is only in contact with the inner surfaces of the ends, the water cannot cool these ends as much as it cools the peripheral walls with which a greater quantity of water is in contact. Therefore in order to prevent injurious expansion or contraction I prefer to shape the core in such a manner that the diameter of the bore decreases from the ends of said bore toward the central transverse plane of the cylinder so that the cylindrical wall will be thicker at the transverse central plane of the roller than they are at or adjacent to the inner surfaces of the ends and I also prefer to shape the core in such a manner that the thickness of the cylindrical walls gradually increases interiorly from the ends of the bore toward the longitudinal central transverse plane of the cylinder as shown for example in Fig. 1, as thereby the distribution of metal is such that the cooling effect of the water is substantially the same throughout the entire cylinder and consequently no undue or harmful contraction or expansion can take place which would tend to throw the cylinder out of true. The amount to which the thickness of the peripheral wall is increased at or near the central transverse plane in relation to the thickness of the walls at the inner surface of the ends of course depends upon the diameter and length of the roller. For the purpose of introducing the cooling water and producing the perfect circulation of the same so that all parts of the bore come in contact with the circulating cooling water I prefer to fix the roller on a shaft 3 extending longitudinally through the ends and bore of the cylinder which shaft is provided at each end with a central longitudinal conduit 4 which extends inward beyond the inner surface of an end of the cylinder and by a short branch conduit 5 is brought into communication with the bore of the cylinder so that the cooling water can enter through one of the conduits 4 of the shaft 3, then

pass into the bore of the roller 1 and pass out through the conduit 4 at the opposite end of the shaft 3 and in circulating through said conduit cools the walls of the 5 roller.

Having described my invention what I claim as new and desire to secure by Letters Patent is:—

1. A crushing roller having end bearings, 10 a cylindrical outer surface and a bore of varying diameter, substantially as set forth.

2. A crushing roller having end bearings, a cylindrical outer surface and a bore of varying diameter, means for circulating a 15 cooling medium through said bore, substantially as set forth.

3. A crushing roller having end bearings, a cylindrical outer surface and a bore of less diameter at the central transverse plane of 20 the cylinder than at the ends of said bore, whereby the thickness of the cylindrical walls of the roller are greater at the central transverse plane of the roller than at the ends, substantially as set forth.

4. A crushing roller having end bearings, 25 a cylindrical outer surface and a bore gradually decreasing in diameter from the ends of the roller toward the central transverse plane whereby the thickness of the cylindrical walls of the roller gradually decrease 30 from the central transverse plane toward the ends, substantially as set forth.

5. The combination with a roller having a bore of varying diameter, of a shaft on which said roller is mounted, said shaft having a conduit extending inward beyond the inner surface of the end or head of the roller and a conduit extending from the inner end of said conduit in the shaft to the bore of 35 the roller, substantially as set forth. 40

Signed at New York city, borough of Manhattan, in the county of New York and State of New York, this 16th day of October A. D. 1913:

MYRON A. SMITH.
